UNITED STATES PATENT OFFICE.

JAMES F. QUINN, OF LOWELL, MASSACHUSETTS, ASSIGNOR TO THE KIMBALL SYSTEM, INC., OF LOWELL, MASSACHUSETTS, A CORPORATION OF MASSACHUSETTS.

DESIGN FOR AN OUTDOOR SIGN.

Application filed November 16, 1923. Serial No. 7,786. Term of patent 14 years.

To all whom it may concern:

Be it known that I, JAMES F. QUINN, a citizen of the United States, residing at Lowell, in the county of Middlesex, and State of Massachusetts, have invented a new, original, and ornamental Design for an Outdoor Sign, of which the following is a specification, reference being had to the accompanying drawings, forming a part thereof.

The figure is a front elevation of an outdoor sign showing my new design.

The sign comprises essentially a series of panels for the reception of advertising matter formed upon a background designed to merge into the surrounding scenery in such a manner that the panels stand out in relief as individual signs.

I claim:

The ornamental design for an outdoor sign as shown and described.

JAMES F. QUINN.
